UNITED STATES PATENT OFFICE.

EMIL F. FLUES, OF BUFFALO, NEW YORK.

AUTOMATIC COMPENSATING BOLT FOR FIREARMS OF THE BREAKDOWN TYPE.

1,312,170.

Specification of Letters Patent.

Patented Aug. 5, 1919.

Application filed November 22, 1917. Serial No. 203,363.

To all whom it may concern:

Be it known that I, EMIL F. FLUES, a citizen of the United States, residing at Buffalo, in the county of Erie and State of New York, have invented certain new and useful Improvements in Automatic Compensating Bolts for Firearms of the Breakdown Type, of which the following is a specification.

10 My improvement relates to firearms such as shot guns and rifles of the type known as "break-down", that is, they may be taken apart for convenience in transporting, etc.; and the object of my improvement is to provide means for automatically taking up the 15 wear in the joint occasioned by the firing of the gun and by the "breaking" of the same.

I attain this end by mechanism illustrated in the accompanying drawing consisting of 20 one sheet and in which—

Figure 1 is a fragmentary side elevation of a gun, partly in section, and illustrating my automatic compensating bolt or wedge; Fig. 2 is a vertical transverse sectional view 25 of the same taken in line 2—2, Fig. 1; looking in the direction of the arrow; Fig. 3 is a fragmentary horizontal sectional view taken in line 3—3 Fig. 1, looking in the direction of the arrow; Fig. 4 is a view 30 similar to Fig. 1 but with the barrel and the compensating bolt removed; and Fig. 5 is a perspective view of the compensating bolt *per se*.

1 represents the frame of the gun, 2 represents the barrel, and 3 represents the lug, all of which may be of any suitable well known construction, such as illustrated in the drawing. 4 represents the well known ball and socket joint which is provided between the frame and barrel of the gun so as to permit of the breaking down of the same, though for the purpose of the present invention this joint may be by any well known and suitable construction such as a hinge pin. It has been found that considerable wear occurs in this joint by reason of the firing of the gun and also from the breaking down of the same, and various means of adjustment have heretofore been attempted 45 for compensating for this wear. But these means have always been hand adjustments and have proved more or less inefficient when in the hands of any but a skilled mechanic. The present invention embodies 50 means for automatically compensating for

this wear which means will now be described.

The lug 3 of the barrel of the gun, *i. e.* that portion, flange, or rib, of the barrel which fits into a suitable socket or slot in the frame, is apertured as at 5, for the passage through it of the adjusting bolt or wedge 6. The adjusting bolt or wedge 6 comprises a body portion 7 having a spring-containing hole drilled in its top side and in which hole is seated a spring 8. Two side flanges 9 are secured to the sides of the body portion, or preferably formed integrally therewith, each of said flanges 9 being formed with curvilinear front and rear sides 10, and with downwardly extending portions 11 which contact with opposite sides of the lug of the barrel when the bolt is in place, and guide the bolt in its movements up and down in the lug. To 75 secure the bolt in place in the aperture of the lug, a set screw 12 is screwed into the lug after the bolt is in place and effectually locks the latter in the lug.

The frame 1 of the gun is provided with 80 seats 13 on opposite sides of the slot into which the lug of the barrel is seated, and these seats are formed with curvilinear front sides, and are so located that when the barrel and frame are assembled, the side 85 flanges 9 of the compensating bolt or wedge will fit down into them as shown in Figs. 1 and 3.

The operation of the above mechanism is as follows: The spring 8 tends constantly 90 to force the bolt or wedge 6 down and the downward movement of the bolt brings the curvilinear front face 10 of each of the flanges 9 into contact with the curvilinear front side of the respective seat 13 and 95 tends to wedge the frame forward and the lug rearward. It is obvious, therefore, that any wear in the joint 4 will be immediately and automatically taken up or compensated for by the action of the bolt 6.

100 While it is not absolutely necessary that the faces of the flanges 9 and seats 13 be curvilinear, I find it most desirable that these faces be made with arcuate faces made concentric with the ball of the ball and socket joint.

105 While I have described what I deem to be the best form in which to embody my invention, it is obvious that the exact details as described may be departed from in 110

various particulars without departing from the spirit of my invention, and I do not limit myself to anything less than the whole of my invention as defined by the prior art.

5 And now having fully described my invention, what I claim and desire to secure by Letters Patent is:

1. A compensating bolt for firearms comprising a body portion and flanged portions rigidly secured to opposite sides of said body portion, one of said portions being provided with a spring-seat.

10 2. A compensating bolt for firearms comprising a body portion, and curvilinear flanged portions rigidly secured to opposite sides of said body portion, one of said portions being provided with a spring-seat.

15 3. A compensating bolt for firearms having a spring-containing cavity formed in its top, guiding flanges on its bottom, and a pair of forwardly projecting flanges formed on its sides.

20 4. In a firearm, the combination with the barrel, frame, and connecting lug thereof, of a compensating wedge mounted in said lug and automatically operable to compensate for any wear between the barrel and frame.

25 5. In a firearm of the break-down type, the combination with the barrel and frame thereof and the means for hinging the same together, of means for automatically compensating for wear in such hinge and constantly tending to force said frame and barrel into complete engagement, whereby the breech of the barrel is driven against the face of the frame.

30 6. In a firearm, the combination with the barrel, lug, and frame thereof, of a compensating bolt for automatically taking up any wear between the barrel and the frame, said bolt being mounted in said lug, and means for securely fastening said bolt in said lug and allowing said bolt a limited amount of movement.

35 45 7. In a firearm, the combination with the

barrel and the frame thereof, of the lug for connecting said barrel and frame and provided with an aperture therethrough, a compensating bolt seated loosely in said aperture, means for securing said bolt in said aperture, and a spring seated in said bolt and bearing against said barrel so as to cause said barrel and frame to move into complete engagement.

50 8. In a firearm, the combination of a frame provided with a pair of oppositely disposed seats, a barrel, a lug on said barrel and formed with an aperture therethrough, a bolt seated in said aperture, and means for causing said bolt to bear constantly against one side of said aperture and against one side of each of said seats.

55 9. In a firearm, the combination of a frame provided with a pair of oppositely disposed seats each of which has a curved side, a barrel, a lug on said barrel and provided with an aperture therein, a bolt seated in said aperture and having a pair of oppositely disposed curvilinear flanges, and means for forcing the curved faces of said flanges into contact with the curved sides of said seats.

60 10. In a firearm, the combination of a frame provided with a pair of curved shoulders, a barrel hingedly connected with said frame, and a compensating bolt having a pair of curved shoulders adapted to automatically contact with the first said shoulders and force said frame and barrel into complete engagement, the construction and arrangement being such that said curved shoulders are all arcuate and have a common normal center, and that one of said pairs of shoulders is movable in a straight line with relation to the other of said pairs of shoulders.

70 75 80 85 EMIL F. FLUES.
